UNITED STATES PATENT OFFICE

HARRY ROSS, OF BRONX, NEW YORK, ASSIGNOR TO FUR GUIDE MACHINE CORPORATION, OF NEW YORK, N. Y., A CORPORATION OF NEW YORK

SPOOL HOLDER FOR FUR-SEWING MACHINES

Application filed July 23, 1928. Serial No. 294,812.

This invention relates to sewing machines, and particularly to a spool holder for a fur sewing machine, although it is not necessarily limited to use with this type of machine, and 5 has for an object to provide an improved spool holder which will permit quick change from one colored thread to another and facilitate the replenishing of the thread when one spool is exhausted, and in which after 10 one spool is exhausted a new and filled spool may be substituted therefor with a quick and simple operation, thus greatly reducing the time the machine must be stopped for changing the thread or for renewing the 15 thread.

With the foregoing and other objects in view the invention consists in certain novel features of construction, combinations and arrangements of parts as will be more fully 20 described in connection with the accompanying drawing. In this drawing,

Fig. 1 is a side elevation of a fur sewing machine with my improved spool holder applied thereto, a portion of the spool and 25 its support being shown in section.

Fig. 2 is a top plan view of the holder.

Fig. 3 is a detail section substantially on line 3—3 of Fig. 1, and

Fig. 4 is a section substantially on line 4—4 30 of Fig. 1.

The frame of the machine is indicated at 10 and has the usual horizontally reciprocating needle and cooperating looper, not shown. At the top of the cover 11 is mounted 35 the tension and guide 12 for the thread 13 taken from a spool 14. An improved support for this spool comprises a head having a body portion 15 and two or more branches 16 extending laterally from the body portion, 40 preferably adjacent the upper end thereof. The body portion 15 has a socket 17 opening through the lower end thereof to receive the end of a supporting rod 18, and a spring 19 in the socket engages at its opposite ends the 45 bottom of the socket and the end of the rod and tends to force the rod outwardly. The body portion 15 has an elongated slot 20 in its side wall which has recesses 21 and 22 at its opposite ends in the lower wall of this 50 slot. The rod 18 carries a pin or screw 23

which projects into this slot and may seat in the recesses 21 and 22 and cooperate with the action of the spring 19 to hold the head in different positions.

Each of the branches 16 carries a support 55 for the spools 14 and 14'. In the form shown it comprises a stud 24 inserted in the branch and threaded at 25 to be threaded into the opening 26 in the center of the spool. Thus the spool may be applied to the head by 60 merely screwing it onto the threaded portion 25, and it may be easily removed therefrom.

The rod 18 is secured to the frame of the machine by any suitable means, such as a 65 bracket 27, secured to the rear wall of this frame by any suitable means, such as screws 28. The bracket has a socket portion 29 to receive the end of the rod 18 and in which it may be secured by any suitable means, such 70 as a transverse pin 30.

The operation is as follows: Assuming the head is in the position of Figs. 1 and 2, the thread is being taken from the spool 14, the spool 14' carrying a different colored thread 75 or being in reserve. If it is desired to use the other colored thread or as soon as the spool 14 is exhausted the operator or assistant merely presses downwardly somewhat on top of the head 15 which will remove the screw or pin 80 23 from the recess 21. The head may then be swung to the left or counterclockwise, as The head will be held in this position by the dotted line position and the spool 14' to the position formerly occupied by the spool 14. The head will be held in this position by the 85 pin or screws 23 seating in the recess 22. The thread may now be taken from the spool 14', and if desired while this is being done if the spool 14 is empty may be removed and a filled 90 spool mounted in its place, or a spool having differently colored thread may be substituted. The head may be swung back to its original position by a similar operation to the one described, bringing the new spool to the position for supplying the thread. This would, if desired, also permit removal of the old spool 14' and the substituting of a new spool 95 therefor.

It will be apparent that this is a very sim- 100

ple arrangement and that when a differently colored thread is desired or when one spool is exhausted, a new spool may be brought to its position with a simple and a quick movement. 5 Also that while the machine is running an empty spool may be removed by an assistant and a new filled spool mounted in its place. Both of these features reduce the time required for changing the thread or renewing 10 thread when a spool is exhausted, and greatly decreases the time the machine must be stopped for these purposes, thus increasing production.

Having thus set forth the nature of my 15 invention, what I claim is:

1. A spool holder for sewing machines including a support, a head mounted for limited turning movement on said support, a plurality of spool holders on said head arranged with their axes at an angle to each other so that turning said head may bring either spool to the operative position, and means yieldingly retaining the head in different 20 positions.

2. A spool holder for sewing machines including a supporting rod, a head having a socket to receive said rod and capable of limited turning movement thereon, a spring tending to force the head longitudinally of 25 the rod and cooperating means on the socket and rod for yieldingly holding the head in different positions under action of said spring, and a plurality of spool holders on said head arranged to support their respective spools in operative position in the different 30 positions of the head.

3. A spool holder for sewing machines including a supporting rod, a head having a socket to receive the end of said rod and provided with an elongated slot in its side wall leading to said socket having recesses adjacent the opposite ends thereof, a pin on the rod extending into said slot, a spring in the 35 socket tending to force the rod outwardly and retain the pin in one of said recesses, and a plurality of spaced spool holders on the head arranged to extend outwardly therefrom.

4. A spool holder for sewing machines including a supporting rod, means for securing 40 said rod to the frame of a machine, a head having a socket to receive the upper end of the rod and having an elongated slot in its side wall leading to said socket provided with recesses at its opposite ends, a pin in the rod 45 extending into said slot and capable of seating in said recesses, a spring in the socket tending to separate the rod and head, branches on the head extending laterally therefrom in different directions, and studs on said branches to support the spools.

In testimony whereof I affix my signature.
HARRY ROSS.
